UNITED STATES PATENT OFFICE.

GEORGE D. EIGHMIE, OF NEW YORK, N. Y.

EXPLOSIVE TURBINE-ENGINE.

Specification of Letters Patent. Patented June 19, 1917.

1,230,139.

Application filed January 11, 1916. Serial No. 71,422.

To all whom it may concern:

Be it known that I, GEORGE D. EIGHMIE, a citizen of the United States, residing at New York, in the county of New York and State of New York, have invented certain new and useful Improvements in Explosive Turbine-Engines, of which the following is a specification, reference being had therein to the accompanying drawing.

10 My invention refers to explosive turbine engines. The object thereof is to furnish a motor of the turbine type operated by the explosions of a gaseous mixture, but simple in construction, having only a few parts, 15 which are related to each other in a convenient and effective way so as to develop large power in a small engine. The invention consists essentially in certain improvements upon the explosive turbine engine de- 20 scribed and claimed in my Letters Patent dated June 20, 1916, No. 1,187,515, for explosive turbine engines; and the invention also comprises numerous details and pecu- 25 liarities in the construction, arrangement and combination of the various parts, substan- tially as will be hereinafter described and then more fully pointed out in the claims.

In the accompanying drawing illustrating my invention:

30 Figure 1 is a vertical section of my improved rotary explosive turbine engine on the line 1, 1 of Fig. 2.

Fig. 2 is a transverse section of the same on the line 2, 2 of Fig. 1.

35 Fig. 3 is a conventional bottom or inside sectional plan or development looking from the inside of the engine of the rings which form the circular valves between the explosion chamber and the turbine blades.

40 Fig. 4 is a conventional development looking from the inside of the engine of the rings which form the valves between the mixing chamber and the explosion chamber, the same being laid out in a straight bottom 45 plan so as to indicate their relation more clearly.

Fig. 5 is an inside view of a development of a modified form of the valves shown in Fig. 3.

50 Fig. 6 is an enlarged detail section on the line 6, 6 of Fig. 5.

Similar characters of reference designate corresponding parts throughout the different figures of the drawing.

55 1 denotes the main horizontal shaft which is hollow and is provided with inlet ports 2

through which the explosive mixture com- 60 ing from any suitable carbureting or other source through the hollow shaft is directed into the interior of the mixing chamber 3. There may obviously be any number of turbine wheels applying their power to the same central rotary shaft 1. I have indicated in the drawings, however, only one of these wheels, as the whole invention can be 65 just as easily explained with one as with several, it being understood that the one serves merely as an example and that it may be multiplied as many times as may be de- 70 sirable. This wheel consists of a narrow rotary cylinder or flanged disk 4 having a hub 5 bolted or otherwise firmly secured to the shaft 1, and a second adjacent flanged disk 6 which is stationary, but permits the shaft 1 to pass through it with a ball bearing 75 7 arranged between them so that the shaft 1 may easily rotate within said disk 6, such rotation being the result of the rotary action of the disk 4 in consequence of the explo- 80 sions within the turbine wheel. The sta- 85 tionary disk 6 is securely bolted or otherwise fastened at its bottom pedestal 8 to a suitable foundation 9. Between the disks 4 and 6 is the mixing or pressure chamber 3 into which the gas or explosive mixture passes 85 from the inlet ports 2.

The revolving disk 4 is provided with a series of curved vanes or fan blades 10 of greater or less length, which are preferably integral with the disk 4 and have a width 90 substantially equal to the space 3. Between the disks 4 and 6 these fan blades revolve rapidly and the suction created thereby draws the gas into the engine.

The stationary disk 6 is provided at a 95 point between its outer periphery and the fan blades 10 with a cylindrical flange 11 which varies in width from one end thereof where its width is substantially nothing, being almost a sharp point, if desired, although 100 it may have a slight width at this point, to another point where its width is nearly equal to the width of the mixing chamber 3, or the distance between the two disks 4 and 6. The varying width of this flange 11 is shown in 105 the bottom or inside plan development of the same, which I have indicated in Fig. 4. The shape of this flange is, therefore, triangular, the base of the triangle being very short in comparison with the sides and the triangle 110 being a right-angled triangle. Closely con- tiguous to the triangular flange 11 is a simi-

lar triangular flange 12 made integral with the revolving disk 4 and overlapping or being overlapped by the flange 11, the degree of overlapping being greater or less as may be desired. These two flanges 11 and 12 together constitute a valve which leads from the mixing chamber 3 into the explosion chamber 13, which latter is an annular chamber between the triangular valve flanges 11 and 12 and other valve flanges of peculiar construction on the outer periphery of the stationary disk 6. Through the valve consisting of overlapping flanges 11 and 12 the explosive mixture passes from the mixing chamber when this valve is open and enters the explosion chamber 13 where it is ignited by a spark from one or more spark plugs 14 or other ignition devices. By referring to Fig. 4 the relation between the two flanges 11 and 12 is more clearly seen as the flanges are there laid out flat. Since flange 11 is stationary, while flange 12 revolves in contact therewith, it is obvious that the edges of these valves will separate during each revolution, opening wider and wider until the point is reached where the widest part of each flange overlaps the narrowest part of the other flange, at which time the valve will be temporarily closed. With a valve constructed in this way the duration of the opening may be considerably longer than the time during which it is closed, but the opening takes place gradually owing to the inclination of the edges of the valve members, and closes gradually when the parts overlap; but it will be understood that by making the narrow ends of the triangular flanges wider or the wider ends narrower, or by doing both, and providing that the overlapping or closed condition of the flanges should continue for a longer time, the duration of the time of opening may be shortened and the quantity of the explosive mixture passed through the valve during its opening may be lessened, or in other words, by properly proportioning and relating the parts the timing of their operation may be regulated to correspond with the requirements of the engine in practice.

The stationary disk 6 is also provided at its outer periphery with another cylindrical flange 15 which is similar to the flange 11 excepting that instead of consisting when laid out flat, as shown in Fig. 3, of a single right-angled triangle extending the entire circumference, it consists of two right-angled triangles arranged tandem to each other, as shown at 16, 16 in Fig. 3, so as to provide two halves instead of one, each valve being similar to the valve composed of the triangular flanges 11 and 12. The revolving disk 4 is provided at a point closely contiguous to the flange 15 with a similar flange 17, which is similar also to the flange 12, except that instead of being through its en-

tire length a single right-angled triangle, it is made in the form of two right-angled triangles arranged tandem as shown at 18, 18. These two triangular flanges 16 are overlapped to a greater or less extent by the edges of the triangular sections 18, 18 of the contiguous flange 17. Hence, two valves are provided in this way which open and close successively, the degree of opening being in proportion to the size and relative arrangement of the flanges and the extent of their overlapping, the whole arrangement and operation being similar to that of the inlet valve which admits the mixture to the explosive chamber, while these outer peripheral flanges serve as exhaust valves to carry off the products of combustion. The rotary disk 4 is also provided on its outer periphery outside of the valve flanges 15 and 17 with a cylindrical peripheral flange 19 consisting of a series of parallel vanes or blades 20 made by cutting slots through the entire width of flange 19 throughout its entire length, and these vanes or blades 20 are preferably located in an inclined direction. When the explosions occur successively within the explosion chamber 13, the force of the explosions will be directed against the inclined vanes or blades 20 of the flange 19 carried by the revolving disk 4, as I have said, thereby imparting a rotary motion to said disk, and consequently to the shaft 1 to which it is attached.

The operation of my improved explosive engine will be evident from the foregoing description of the construction and arrangement of the various mechanical details without the need of additional explanation. It will be observed that the ports 2 are always open to admit air and gas through the hollow shaft 1 into the interior chamber 3 where it will be drawn in by the suction of the fan blades 10. Immediately after the engine is started and the inlet valve consisting of the triangular flanges begins to operate, charges of the explosive mixture will be successively introduced into the explosion chamber 13, and at the proper moment determined by the timing of the sparking devices each charge will be fired and as the exhaust valves successively open at the outside of the explosion chamber 13, the force of the explosion will act against the exterior vanes 20, causing the disk 4 to rotate and carry with it the hollow central shaft 1, thereby actuating any mechanism with which said shaft may be connected. Obviously the exhaust of the explosions will take place between the vanes or blades 20 into the outer air, while the force of said explosions is imparting motion to the rotary disk 4.

It will be obvious that I am not to be restricted to a single inlet valve in asso-

- ciation with two outlet valves, for it will be easy to increase the number of inlet valves by simply increasing in the same flanges the number of triangular sections 11 and 12 of which the inlet valves are composed, and similarly the number of exhaust valves need not be confined to two as I have indicated in the specimen illustration of the invention given here by way of example, but by increasing the number of triangular sections 16 and 18 of the flanges 15 and 17 I can obviously increase the number of valves and modify the operation accordingly. It will be clear, therefore, that in building these engines for actual use, the duty required of them will be taken into account in the provision of the number of valves and ignition devices and their relative location, operation and timing.
- 20 In Fig. 5 I have indicated a modification of my invention which resides in omitting the valve flange 17 on the rotary disk 4 and in forming vanes or blades 20^a in the peripheral flange 19 so that they will be arranged in two or more triangular series, corresponding in number to the exhaust valves used in the particular engine, these vanes 20^a being separated by slots which vary in length from those running almost the entire width of the flange 19 down to a point where they are very small, the series being triangular as stated and as clearly shown in Fig. 5. Thus the valves in this modification consist of a flange having a series of slots 30 varying in size so that the whole line of them is arranged in triangular form, and being cut from the edge of the flange 19 inwardly in this manner, and the flange 15 which is formed in the same manner as before with sections of triangular form which overlap the triangular series of slots and operate to uncover these slots in the same manner as in Fig. 3, and the flanges 15 and 17 are released from each other in opening and closing the valves, the effect and result being obviously substantially the same.
- It will be noted that various changes in the precise structure of the several parts may be made without exceeding the scope of the invention or affecting the value of the claims, and I, therefore, reserve the liberty not only of changing the number and arrangement of the inlet and outlet valves as already suggested, but also of making all other desirable changes as experience may prove to be wise and expedient.
- Having thus described my invention, what I claim as new and desire to secure by Letters Patent is,—
- 60 1. In an internal combustion engine, a pair of disks, one revolving and one stationary, between which there is a central mixing chamber and a circumferential explosion chamber, the revolving disk carrying a series 65 of fan blades in the mixing chamber and at its periphery a series of vanes, an inlet valve for allowing the explosive mixture to pass from the fan into the explosion chamber, said valve consisting of overlapping triangularly-shaped flanges, one on the stationary disk and one on the revolving disk whose edges engage and disengage so as to open a passage at times and close it at other times, and a valve between the explosion chamber and the peripheral vanes, by means 70 of which the force of the explosion acts against the vanes and imparts a rotary motion to the revolving disk.
2. In an internal combustion engine, a pair of disks, one revolving and one stationary, between which there is a central mixing chamber and a circumferential explosion chamber, the revolving disk carrying a series of fan blades in the mixing chamber and at its outer periphery a series of 80 vanes, an inlet valve for allowing the explosive mixture to pass from the fan into the explosion chamber, said valve consisting of concentric flanges, one on the stationary disk and one on the revolving disk, whose contiguous edges are inclined to the plane of the disk so that during the revolution of the disk said edges will separate at times to provide a passage and will come together at other times to close the passage, and a valve 85 between the explosion chamber and the peripheral vanes, by means of which the force of the explosion acts against the vanes and imparts a rotary motion to the revolving disk.
3. In an internal combustion engine, a pair of disks, one revolving and one stationary, between which there is a mixing chamber near the center and an explosion chamber near the circumference, the revolving disk having peripheral vanes outside of the explosion chamber, an inlet valve for allowing the explosive mixture to pass from the mixing chamber into the explosion chamber and consisting of angular flanges, 100 one on the stationary disk and one on the revolving disk, whose edges engage and disengage so as to open a passage at times and close it at other times, and an exhaust valve between the explosion chamber and the peripheral vanes, and consisting of angular flanges, one on the stationary disk and one on the revolving disk, whose edges engage and disengage so as to allow a passage to be opened at times and closed at other times, 105 whereby the force of the explosions may be exerted against the peripheral vanes to impart rotary motion to the revolving disk.
4. In an internal combustion engine, a pair of disks arranged parallel to each other, 110 one revolving and one stationary, the revolving disk carrying a series of fan blades, and at its outer periphery a series of vanes, an inlet valve for allowing the explosive mixture to pass from the fan into the ex- 115 120 125 130

losion chamber, said valve means consisting of a flange on the stationary disk and a contiguous flange on the revolving disk, the edges of which flanges separate at times 5 so as to provide a passage between them, an exhaust valve means between which and the inlet valve means is the explosion chamber, said exhaust valve means consisting of a flange on the stationary disk contiguous to 10 the outer vanes of the revolving disk, and also a flange on the revolving disk, the edges of which flanges separate at times to provide a passage between them through which the force of the explosion may act against 15 the turbine vanes and then exhaust to atmosphere.

5. In a rotary explosive engine, the combination of a revolving disk, having a peripheral flange formed with vanes, and having also a series of fan blades, a stationary disk parallel to the revolving disk and between which and the revolving disk is a central mixing chamber and a circumferential explosion chamber, an inlet valve 20 between the mixing chamber and the explosion chamber consisting of cylindrical overlapping flanges, one on the revolving disk and one on the stationary disk, each flange consisting of one or more triangular sections 25 whose edges engage and disengage so as to open a passage at times and close it at other times, and an exhaust valve between the explosion chamber and the peripheral vanes and consisting of overlapping cylindrical 30 flanges, one on the stationary disk and one on the revolving disk, and each flange having one or more triangular sections whose edges engage and disengage so as to open 35 passages at times and close them at other 40 times.

6. In an internal combustion engine, a pair of disks, one revolving and one stationary, the revolving disk having a peripheral cylindrical flange formed with vanes and having also a series of fan blades, an inlet valve for allowing the explosive mixture 45 to pass from the fan into the explosion chamber, said valve consisting of overlapping flanges on the disks, the edges of which flanges are inclined to the plane of the disks so as to move toward and away from each other to open and close a passage, and valve mechanism between the explosion chamber and the peripheral vanes consisting likewise 50 of overlapping flanges on the disks, the edges of which flanges are inclined to the plane of the disks so as to move toward and away from each other to open a passage at times and close it at other times.

60 7. In an internal combustion engine, a pair of disks, one revolving and one stationary, between which there is a central mixing chamber and a circumferential explosion chamber, the revolving disk having

70 peripheral vanes and also a series of fan blades in the mixing chamber, an inlet valve mechanism between the mixing chamber and the explosion chamber, and an exhaust valve mechanism between the explosion chamber and the peripheral vanes, said latter mechanism consisting of overlapping flanges, the edges of which flanges have one or more sections whose edges are inclined to the plane of the disks to that during the revolution of the wheel said edges will separate at times to provide one or more passages and will come together at other times to close the passages, whereby the force of the explosions acts against the peripheral vanes so as to impart rotary motion to the 80 revolving disk.

8. In an internal combustion engine, a pair of disks, one revolving and one stationary, between which there is a central mixing chamber and a circumferential explosion chamber, the revolving disk carrying a series of fan blades in the mixing chamber and at its outer periphery a series of vanes, an inlet valve for allowing the explosive mixture to pass from the fan into 85 the explosion chamber, said valve consisting of overlapping triangularly-shaped flanges, one on the stationary disk and one on the revolving disk whose edges engage and disengage so as to open a passage at times and 90 close it at other times, and a valve between the explosion chamber and the peripheral vanes, by means of which the force of the explosion acts against the vanes and imparts a rotary motion to the revolving disk, and 95 a hollow shaft having ports leading into the mixing chamber, to which shaft the revolving disk is secured for the purpose of imparting motion thereto as it revolves.

9. In a rotary explosive engine, the combination of a revolving disk, having a peripheral flange formed with vanes, and having also a series of fan blades, a stationary disk parallel to the revolving disk and between which and the revolving disk is a central mixing chamber and a circumferential explosion chamber, an inlet valve between the mixing chamber and the explosion chamber consisting of cylindrical overlapping flanges, one on the revolving disk and one on the stationary disk, each flange consisting of one or more triangular sections whose edges engage and disengage so as to open a 100 passage at times and close it at other times, and an exhaust valve between the explosion chamber and the peripheral vanes and consisting of overlapping cylindrical flanges, one on the stationary disk and one on the revolving disk, and each flange having one or 105 more triangular sections whose edges engage and disengage so as to open passages at times and close them at other times, and a hollow shaft having ports leading into the 110 mixing chamber, to which shaft the revolving disk is secured for the purpose of imparting motion thereto as it revolves.

115 120 125

mixing chamber, to which shaft the revolving disk is attached, together with ignition means in the explosion chamber.

10. In an internal combustion engine, a
5 pair of disks forming a wheel, one disk revolving and one stationary, between which there is a central mixing chamber and a circumferential explosion chamber, the revolving disk carrying a series of fan blades in
10 the mixing chamber and at its outer periphery a series of vanes, a hollow shaft having ports leading into the mixing chamber, to which shaft the revolving disk is secured, an inlet valve for allowing the explosive
15 mixture to pass from the fan into the explosion chamber, said valve consisting of cylindrical flanges whose edges are parallel to each other and inclined from one end to the other, the angle of inclination being
20 acute to the plane of the disk so that during the revolution of the wheel, the edges will

separate at times to provide a passage for the mixture from the mixing chamber into the explosion chamber and will come together at other times to close said passage, 25 and exhaust valve mechanism between the explosion chamber and the peripheral vanes and consisting of cylindrical flanges, shaped as triangular sections, one of said flanges being on the stationary disk and the other on 30 the revolving disk, the edges of the flanges being inclined to the plane of the disk and engaging each other so that during their revolution passages will be opened between the explosion chamber and the peripheral 35 vanes and at other times will be closed so that the force of the explosions may act on said vanes, and ignition means within the explosion chamber whereby the successive charges of the mixture are fired. 40

In testimony whereof I affix my signature.

GEORGE D. EIGHMIE.
